(57) **CLAIM**

The ornamental design for a magnetic folding wireless charger, as shown and described.

DESCRIPTION

FIG. 1 is a front perspective view of a magnetic folding wireless charger, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a rear perspective view of the magnetic folding wireless charger, shown folded in a second configuration; and,

FIG. 10 is a front perspective view thereof.

The broken lines depict elements of the magnetic folding wireless charger that form no part of the claimed design.

1 Claim, 10 Drawing Sheets
